UNITED STATES PATENT OFFICE.

HARVEY A. MOYER, OF SYRACUSE, NEW YORK, ASSIGNOR OF ONE-HALF TO EMMIT G. LATTA, OF SYRACUSE, NEW YORK.

TYPE-WRITING MACHINE.

1,164,660.

Specification of Letters Patent. Patented Dec. 21, 1915.

Application filed February 3, 1908. Serial No. 413,942.

To all whom it may concern:

Be it known that I, HARVEY A. MOYER, a citizen of the United States, residing at Syracuse, in the county of Onondaga and State of New York, have invented a new and useful Improvement in Type-Writing Machines, of which the following is a specification.

This invention relates to typewriting machines of that kind which are provided with a plurality of sets of type, one of which sets is normally in printing relation with the platen, while the printing relation between the other set of type and the platen is secured by shifting either the platen or the support for the type-bars or other type carriers.

The primary object of the invention is to produce an efficient and desirable shifting mechanism of exceedingly simple and inexpensive construction adapted, by the simple depression of a shift key or lever, to produce a variable motion of the shifting part, whether the platen or the type-support, for starting the same slowly, then accelerating and finally retarding its motion as it approaches the limit of its movement, whereby the shift can be effected quickly and with less exertion, noise and shock than usual; also to construct the shifting mechanism so that in addition to accomplishing these results the device, which effects the shift without the addition of other parts, will positively hold the shifting part from rebounding or vibrating when shifted from either of its positions to the other; also to so construct and arrange the shifting mechanism that it will afford a firm stable support for the shifting part but will nevertheless consist of fewer parts than ordinarily required; and to improve the construction of shifting mechanisms for the intended purpose in the particulars hereinafter described and set forth in the claims.

In the accompanying drawings, consisting of four sheets: Figure 1 is a fragmentary longitudinal sectional elevation of a typewriting machine provided with mechanism embodying the invention for shifting the platen carriage. Fig. 2 is a transverse sectional elevation thereof, in line 2—2, Fig. 1, omitting the platen carriage. Fig. 3 is a fragmentary longitudinal sectional elevation of a slightly modified construction. Fig. 4 is a transverse section of the shifting cam

and coöperating bearing part, in line 4—4, Fig. 3. Fig. 5 is a fragmentary longitudinal sectional elevation of a typewriting machine provided with mechanism embodying the invention for shifting the type-bar segment or support.

Like letters of reference refer to like parts in the several figures.

A represents the stationary frame of the machine, B the platen, C the carriage on which the platen is journaled and which, as usual, travels transversely of the machine, and D one of the type-bars. A visible writing machine is illustrated in which the type-bars are pivoted on a segment or support d located below the platen and swing upwardly and rearwardly to make the impressions at the front side of the platen. These parts may be of the usual or any suitable construction. The type-bars are furnished with two sets of type, one of which is normally in proper relation to the platen for printing, while the other set of type can be placed in such printing relation either by shifting the platen or the type-bar support.

In the constructions shown in Figs. 1—4, the type-bar support is stationary and the platen carriage is shifted, for which purpose the carriage is preferably supported by and travels transversely on a shift frame E which is pivoted at the opposite ends of its rear portion to the upper rear portion of the frame A, at e, in any suitable manner, so that it can swing vertically. A spring e', Fig. 1, is shown connected at opposite ends to the main frame and to a lug on the shift frame for counterbalancing the weight of the shift frame and carriage which it supports.

F represents a rock arm which is pivoted in the lower portion of the machine and supports the front central part of the shift frame. A cam bearing or connection is provided between the rock arm and the shift frame for swinging the latter vertically when the arm is rocked.

In the construction shown in Figs. 1 and 2, the upper end of the rock arm is forked and a bearing roller f journaled therein works in a reversely curved cam slot g in a depending cam portion G of a bracket H which is secured to or formed on and projects forwardly from the central portion of the shift frame. The bracket H shown is slotted at h to receive the vibrating ribbon

guide h' and its support h^2 and operating lever h^3 .

The rock arm could be pivotally supported in any suitable manner, but is preferably secured to the central part of a horizontal rock shaft I which is journaled at its ends in suitable bearings i on the sides of the main frame, and at its central portion in a bearing bracket i' .

10 K K represent two shift key-levers preferably arranged longitudinally at opposite sides of the machine and suitably fulcrumed between their ends, for instance, on pivots k projecting from the sides of the main frame. 15 The front ends of the levers are furnished with finger keys (not shown), and the upper edges of their rear ends are convexed or rocker-shaped and bear against the lower edges of rocker arms k' which are secured 20 to and project forwardly from the rock shaft I. The key levers are held in the normal position with their front ends raised, and returned to such position after actuation, by springs k^2 , one of which is shown in 25 Fig. 1, coiled around their pivot bearings and connected to the levers and bearings, and the rock arm is pushed forwardly with 30 its bearing roller f in the front end of the cam slot g , and the rocker arms k' held down on the key levers by springs k^3 , Figs. 1 and 35 2, coiled around the opposite ends of the rock shaft and connected to the same and to the bearings for the rock shaft. Any other suitable means for returning the key levers and rock arm to the normal position could, however, be employed.

The described connections between the shift keys and rock arm are desirable for the following reasons: They give the shift 40 keys great leverage at the commencement of their movement while they are overcoming the inertia of the shifting parts, and the leverage decreases as the movement continues, so that the shifting parts start easily 45 and the operator's fingers are relieved from shock, while the full depression of the shift key can be made with but little difference in the force required. The shift keys move smoothly and friction between the same and 50 the rocker arms is practically eliminated, and the rock arm can be actuated by the depression of either shift key and the other key will remain stationary in its normal position. The rock arm could, however, be pivoted in the machine and operated by any 55 other suitable connections from a shift key or keys conveniently located. Another connection which is shown in Fig. 5 will be described later.

60 The cam slot g , as stated, is in the form of a reverse curve and it is so disposed with reference to the pivotal axes of the shift frame and rock arm that when the bearing roller f is in its normal position in the front 65 end of the slot, two lines x and y , Fig. 1, in-

tersecting at right angles at the center of the roller will pass through the axes of the shift frame and rock-arm. Several important results are incident to this arrangement, viz.:—It enables the roller to move 70 slightly before starting the shift frame and to then start the shift frame with a slow motion, which gradually increases until the roller reaches about the middle of the slot, and then gradually decreases and finally 75 ceases just before the roller completes its movement. The shift frame can therefore be started easily and the gradual stopping thereof prevents vibration of the same, and the platen which it supports, which causes 80 an imperfect alinement if a type-bar is actuated simultaneously with the shift key. The cam slot, owing to its upper and lower edges being in contact with the opposite sides of the bearing roller in the center line 85 of the rock-arm, positively holds the shift frame from vibrating in either direction when it is allowed to fall back to the normal position; and it also effectually holds the shift frame from vibrating in the shifted 90 position. This action is not so positive in the shifted position, because the cam slot should be of such curvature as to allow the roller to be started back to the normal position by the return springs for the rock- 95 arm, but the tendency of the shift frame to rebound or vibrate in the shifted position is not so great as in the normal position, because the operator's finger is always on the shift key when the parts reach the shifted 100 position. Thus the shift frame is started slowly and its motion is first accelerated and then retarded to prevent the shock of a sudden stop, and it is effectually held against rebounding or vibrating in both its 105 normal and shifted positions by the roller and slotted cam without requiring any additional parts.

Instead of the described relative arrangement of the bearing roller and cam slot, the 110 cam could be arranged to locate the roller at the intersection of the described lines x and y when in the rear end of the slot in the shifted position of the parts, or when at a point between the ends of the slot, with 115 good results, but the described arrangement is preferred. By locating the shifting cam connection at the central front portion of the shift frame, it, together with the pivots e , forms a very firm or stable three-point or 120 triangular support for the shift frame and greatly simplifies the construction, as only one shifting device is required, which reduces the number and weight of the parts of the mechanism, and it is much easier to 125 make a single device work properly than to make two such devices work in unison. The slotted cam and bearing roller constitute a stop which limits the movements of the shift frame in both directions, with much less 130

noise than the stops usually employed; they prevent the shift frame from overrunning the movement of the shift key, and also hold the shift frame from movement in case the 5 machine is turned upside down. The rock-arm F forms a rigid brace between its pivotal support and the shift frame, and as the severe strains caused by the tendency of the shift frame to rebound act in the direction 10 of the length of the arm, the rock-arm, together with the widely separated pivots e at the rear of the frame, forms a very stable support for the shift frame.

While the cam has been described as being 15 in the form of a reverse curve, and adapted to produce both an accelerating and a retarding motion of the shifted part, this shape is not necessary when a rocker shift lever is used to operate the cam, as that provides 20 the accelerating motion, and the decreasing leverage of the rocker shift lever acts to prevent shock to a great extent when the parts reach shifted position. The intermediate portion of the cam should, however, 25 be oblique or inclined to effect the shift, and the end portions thereof that form the rests for the roller are made one on each side of the line of the oblique portion of the cam to enable the roller to positively lock the 30 shift frame against rebound. The essential point is to make the cam with a part at each end that permits the roller to move thereon after the shift is effected, and before the shift movement begins, without disturbing 35 the position of the shift frame, and to locate the pivots of the rock-arm and shift frame so that any tendency of the shift frame to move either up or down when the roller is in either of its rest positions will be in the 40 direction of the length of the arm or on a line radial with the pivotal axis of the rock-arm so that the arm acts as a lock to prevent movement of the shift frame in either direction. By providing this slight dwell, 45 or movement of the roller into and out of its rest positions without moving the shift frame, the parts form a positive lock for the shift frame in both its positions and entirely overcome the trouble heretofore caused by the 50 tremulous action of the shifted part when doing rapid work. The rest parts of the cam are made long enough to permit the shift arm to vibrate slightly without moving the roller into the oblique operative part 55 of the cam, and such vibration of the arm does not permit the shift frame to vibrate.

Suitable means are preferably provided, as usual, for locking the shift frame in the shifted position without requiring the shift 60 key to be held down, but such means form no part of the invention and are not shown.

Figs. 3 and 4 illustrate a shifting mechanism in which the cam connection between the rock-arm and shift frame is reversed, the 65 cam G' being formed on or secured to the

rock-arm F' while the bearing roller f' is journaled on the bracket or extension H' on the shift frame. The roller is journaled on a stud f² projecting from one side of the bracket H' for the purpose of enabling a 70 ready detachment of the shift frame from the machine. By loosening the pivots for the shift frame, the frame can be lifted clear of the pivot supports on the main frame and then moved sidewise to disengage the roller 75 f' from the cam slot g'. In this modification the roller normally occupies the rear end of the cam slot as the rock-arm is swung rearwardly to effect the shift, and the pivotal axis of the rock-arm F' is located higher 80 than in the other construction, but the location of the axis of the rock arm is unimportant so long as the bearing roller f' occupies substantially the relation to the axes 85 of the shift frame and rock-arm before described.

Fig. 5 shows a mechanism embodying the invention for shifting the type-bar segment or support instead of the platen. In this construction the segment d² is supported so 90 as to move vertically on upper and lower parallel links or arms L and M. The upper links L are pivoted at l to the ends of the segment and secured to the opposite ends of a rock shaft l' suitably journaled on the 95 main frame, while the lower link M is suitably pivoted at its front end at m to the central part of the segment and at its rear end at m' to the main frame. The segment is thus held upright but permitted to move vertically. F² is a rock-arm provided at its upper end with a bearing roller f³ working in a reversely curved cam slot g² in the lower supporting link M for the segment. The rock-arm is secured at its lower end to a rock 100 shaft I² suitably journaled in the main frame. When the rock-arm F² is swung rearwardly or forwardly, the bearing roller working in the cam slot will raise or lower the segment, producing an accelerating and 105 retarding motion thereof similar to that of the shift frame produced by the roller and reversely curved slot in the other constructions. Obviously, the cam slot could be provided in the rock-arm F² and the roller secured to the segment-supporting link M, or either the cam or roller could be provided directly on the segment instead of on the supporting link, and the segment movably supported in any other suitable way without 110 affecting the cam action. The rock-arm F² 115 can be operated by rocker connections from the shift keys, as before described, or by any other suitable means. As shown, links n are pivoted to the shift key levers K² and slotted to receive pins n' on arms n² secured to the rock shaft I², whereby the rock-arm F² will be oscillated when either shift key is operated and either key can remain stationary 120 when the other is actuated. The link con- 125 130

nection shown in Fig. 5 could, if desired, be used in the other constructions described.

I claim as my invention:

1. In a typewriting machine, the combination with a member which is shiftable to change the printing relation of the platen and type, of coöperating relatively movable parts one of which has a cam which engages the other part and one of which parts is connected to said member, means for moving one of said parts in one direction from one position to another, and means for causing the return movement of said part, said cam having an oblique middle portion which acts to shift said member when said movable part is moved and end portions which act to hold said member from vibration when said movable part is in either of its rest positions, substantially as set forth. 70
2. In a typewriting machine, the combination with a member which is shiftable to change the printing relation of the platen and type, of shifting means for said member comprising a stud, and a cam having a cam slot in which said stud slides, one of said parts being connected to said shiftable member, a rock arm carrying said other part, means for moving said rock arm in one direction from one position to another, and means for causing the return movement of said rock arm, said cam slot having a portion which extends obliquely to the arc of movement of said rock arm and acts to shift said member when said rock arm is moved and opposing faces substantially concentric with the pivotal axis of said rock arm which engage said stud and act to hold said member from vibration when said rock arm is in either of its rest positions. 80
3. In a typewriting machine, the combination with a member which is shiftable to change the printing relation of the platen and type, of coöperating relatively movable parts one of which has a cam slot in which the other part slides, one of said parts being connected to said shiftable member and one being a rock arm for shifting said member, a key lever having a rocker connection with said rock arm for moving said rock arm in one direction from one position to another, and means for causing the return movement of said rock arm, said cam slot having a shifting portion which extends obliquely to the arc of movement of said rock arm and acts to shift said member when said rock arm is moved and holding portions which act to hold said member from vibration when said rock arm is in either of its rest positions, substantially as set forth. 90
4. In a typewriting machine, the combination with a member which is shiftable to change the printing relation of the platen and type, of a rock-arm having a cam slot, a part connected to said member and arranged to slide in said cam slot, means for moving said rock-arm in one direction from one position to another, and means for causing the return movement of said rock-arm, said cam slot having an oblique middle portion which acts to shift said member when said rock-arm is moved and end portions substantially concentric with the pivotal axis of the rock-arm which act to hold said member from vibration when said rock-arm is in either of its rest positions, substantially as set forth. 95
5. In a typewriting machine, the combination with a member which is shiftable to change the printing relation of the platen and type, of coöperating relatively movable parts one of which has a reversely-curved cam face which is held in sliding engagement with said other part, one of said parts being connected to said member, means for moving one of said parts in one direction from one position to another, and means for causing the return movement of said part, said cam face having an oblique portion which acts to shift said member when said movable part is moved and portions arranged to hold said member from vibration when said movable part is in either of its rest positions, substantially as set forth. 100
6. In a typewriting machine, the combination with a member which is pivotally supported at one side and is shiftable to change the printing relation of the platen and type, of coöperating relatively movable parts which are located substantially midway between the ends of said shiftable member at the opposite side thereof and one of which has a cam which is held in sliding engagement with said other part, one of said parts being connected to said member, means for moving one of said parts in one direction from one position to another, and means for causing the return movement of said part, said cam having a shifting portion which acts to shift said member when said movable part is moved and holding portions which act to positively hold said member from vibration when said movable part is in either rest position, substantially as set forth. 105
7. In a typewriting machine, the combination with a member which has bearings at its opposite sides and is shiftable to change the printing relation of the platen and type, of coöperating relatively movable parts which are located substantially midway between the sides of said member and form with said bearings a triangular support for said member and one of which has a reversely curved cam face which is held in sliding engagement with said other part, one of said parts being connected to said member, means for moving one of said parts in one direction from one position to another, and means for causing the return movement of said part, said coöperating parts acting to 110
8. In a typewriting machine, the combination with a member which is shiftable to change the printing relation of the platen and type, of coöperating relatively movable parts which are located substantially midway between the ends of said member and form with said bearings a triangular support for said member and one of which has a reversely curved cam face which is held in sliding engagement with said other part, one of said parts being connected to said member, means for moving one of said parts in one direction from one position to another, and means for causing the return movement of said part, said coöperating parts acting to 115
9. In a typewriting machine, the combination with a member which is shiftable to change the printing relation of the platen and type, of coöperating relatively movable parts which are located substantially midway between the sides of said member and form with said bearings a triangular support for said member and one of which has a reversely curved cam face which is held in sliding engagement with said other part, one of said parts being connected to said member, means for moving one of said parts in one direction from one position to another, and means for causing the return movement of said part, said coöperating parts acting to 120
10. In a typewriting machine, the combination with a member which is shiftable to change the printing relation of the platen and type, of coöperating relatively movable parts which are located substantially midway between the ends of said member and form with said bearings a triangular support for said member and one of which has a reversely curved cam face which is held in sliding engagement with said other part, one of said parts being connected to said member, means for moving one of said parts in one direction from one position to another, and means for causing the return movement of said part, said coöperating parts acting to 125
11. In a typewriting machine, the combination with a member which is shiftable to change the printing relation of the platen and type, of coöperating relatively movable parts which are located substantially midway between the ends of said member and form with said bearings a triangular support for said member and one of which has a reversely curved cam face which is held in sliding engagement with said other part, one of said parts being connected to said member, means for moving one of said parts in one direction from one position to another, and means for causing the return movement of said part, said coöperating parts acting to 130

shift said member when said movable part is moved and to automatically hold said member from vibration when said movable part is in either rest position, substantially as set forth.

8. In a typewriting machine, the combination of a member which is pivotally supported at one side thereof and is shiftable to change the printing relation of the platen and the type, a single rock-arm which forms the sole support for the opposite side of said member and is located substantially midway between the ends of said member, a cam and a part held in sliding engagement therewith which connect said rock-arm to said member, and means for operating said rock-arm, said cam having a face which acts to shift said member when said rock-arm is moved and a face at the end of said shifting face which acts to positively hold said member from vibration, substantially as set forth.

9. In a typewriting machine, the combination of a member which is shiftable to change the printing relation of the platen and the type, a single rock-arm which is located substantially midway between the ends of said member, a cam on said rock-arm, a part connected to said member and held in sliding engagement with said cam, and means for moving said rock-arm in opposite directions, said cam having an oblique face which acts to shift said member when said rock-arm is moved and faces at opposite ends of said oblique face which act to positively hold said member from vibration when said rock-arm is at either limit of its movement, substantially as set forth.

10. In a typewriting machine, the combi-

nation with a platen and type, of a shift frame for the platen arranged to oscillate about an axis in rear of the platen, co-operating relatively movable parts one of which has a reversely curved cam face which is held in sliding engagement with said other part, one of said parts being connected to the front central portion of said shift frame, means for moving said other part in one direction from one position to another, and means for causing the return movement of said movable part, said co-operating parts acting to shift said shift frame when said movable part is moved and to automatically hold said shift frame from vibration when said movable part is in either of its rest positions, substantially as set forth.

11. In a typewriting machine, the combination with a platen and a series of type-bars each having a plurality of type, of a shift frame for the platen arranged to oscillate about a pivotal axis at its rear, a rock-arm, and means for rocking the same, and a cam and co-operating part connecting the free end of said arm to the front central part of the shift frame, said cam being located at the intersection of lines crossing at substantially right angles and extending through the pivotal axes of the shift frame and said rock-arm, substantially as set forth.

Witness my hand, this 28th day of January, 1908.

HARVEY A. MOYER.
